(57) **CLAIM**

The ornamental design for a nail file, as shown and described.

DESCRIPTION

FIG. 1 is a top plan view of a first embodiment of a nail file, showing our new design;

FIG. 2 is a bottom plan view thereof;

FIG. 3 is a right side view thereof;

FIG. 4 is a left side view thereof;

FIG. 5 is a front elevational view thereof;

FIG. 6 is a rear elevational view thereof in an upside down orientation relative to FIG. 5;

FIG. 7 is top front perspective view thereof;

FIG. 8 is a top rear perspective view thereof;

FIG. 9 is a bottom rear perspective view thereof;

FIG. 10 is a top plan view of a second embodiment of a nail file, showing our new design;

FIG. 11 is a bottom plan view thereof;

FIG. 12 is a right side view thereof;

FIG. 13 is a left side view thereof;

FIG. 14 is a front elevational view thereof;

FIG. 15 is a rear elevational view thereof in an upside down orientation relative to FIG. 14;

FIG. 16 is top front perspective view thereof;

FIG. 17 is a top rear perspective view thereof; and,

FIG. 18 is a bottom rear perspective view thereof.

The bear symbol in the Figures is a registered trademark of Besweet Creations Inc.
